N. H. CHRISTOFFERS.

METHOD FOR ACCUMULATING AND STORING ENERGY.

APPLICATION FILED APR. 25, 1917.

1,248,807.

Patented Dec. 4, 1917.

Inventor:
Nicholas H. Christoffers
by his attorney, Samuel F. Darby

UNITED STATES PATENT OFFICE.

NICHOLAS H. CHRISTOFFERS, OF NEW YORK, N. Y.

METHOD FOR ACCUMULATING AND STORING ENERGY.

1,248,807.

Specification of Letters Patent. Patented Dec. 4, 1917.

Application filed April 25, 1917. Serial No. 164,469.

To all whom it may concern:

Be it known that I, NICHOLAS H. CHRISTOFFERS, a citizen of the United States, residing at New York, in the county and State of New York, have made a certain new and useful Invention in Methods for Accumulating and Storing Energy.

The object of the invention is to provide a device of the character described which can be attached to any operating mechanism for accumulating and storing power under normal operation, for use when excessive strain or load is placed upon the operating mechanism.

15 Further objects of the invention will appear more fully hereinafter.

The invention consists substantially in the discovery of utilizing the wasted energy in a rotating body, and, in the particular illustration, consists substantially in the construction, combination, location and relative arrangement of parts, all as will be more fully hereinafter set forth, as shown by the accompanying drawing and finally 25 pointed out in the appended claims.

Referring to the drawing:

Figure 1 is a view in elevation of a structure embodying my invention.

Fig. 2 is a view in side elevation of the same.

Fig. 3 is a sectional view taken on the line 3—3, Fig. 1, and looking in the direction of the arrows.

The same part is designated by the same reference numeral wherever it occurs throughout the several views.

I have discovered that a normally rotating body driven from any source under normal conditions, may be utilized to store up power in itself for use when an extra strain or load is imposed upon the source of power. For instance, a fly wheel operated by the gas engine under normal conditions may in itself store up or accumulate power when running idly, for useful work, for example, when an additional strain or load is imposed on the engine. In accordance with my invention the momentum and weight of the fly wheel is utilized for this purpose, and while the subject matter of my invention is a departure to a great extent from the general application of fly wheels, it is believed that with the description thereof hereinafter set forth, it will be apparent that with small expense my invention may be applied readily to any construction where

it is desired with small effort to accomplish results heretofore accomplished only by the use of powerful machines or great power.

Referring to the drawing, I show at 1 a frame which is pivotally carried by journals 2 and 3 which may form part of any suitable stationary frame work by means of sleeves 4^a and 5^a respectively, whereby the frame 1 may rotate freely about said shafts 4 and 5. The shafts 4 and 5 shown in the illustration pass freely through the sleeves 4^a and 5^a and are in the same plane and are off center relative to the central horizontal axis of the frame 1. Mounted on the shaft 5 is a sprocket or other suitable gear 14 adapted to be operated from any suitable source of power in any suitable manner. For the purposes of description, I have shown one means which comprises a chain 15 for this purpose, but it is understood that my invention is not to be limited to this specific form as any other means of transmission of power may be employed. Also mounted on the shaft 5 is a gear wheel 13, which meshes with a gear wheel 12 mounted and secured to the shaft 10 which extends across the horizontal central axis of the frame 1. Mounted on the shaft 10, to rotate therewith is a comparatively large fly wheel 11 with greater peripheral weight than central weight, to secure peripheral momentum upon the rotation thereof. The shaft 10, as shown, is carried by the frame 1.

Also mounted on the shaft 10 to rotate therewith is a gear wheel 9, which gear wheel meshes with a gear wheel 8, mounted on and secured to the shaft 4. Also mounted on and secured to the shaft 4 is a wheel 6, which wheel 6 is connected to the part to be driven which may be any part, and the connection thereof, although shown as a chain 7 may be any suitable connection.

The operation of the device is apparent. The device is connected between the source of power and the part to be driven. Power is transmitted, in the illustration shown, through the chain 15 to wheel 14, thereby rotating the shaft 5 and gear wheel 13, and the rotation of the gear wheel 13 in operation rotates gear 12, fly wheel 11, gears 9, and 8, shaft 4 and consequently gear 6, thus imparting power through the chain 7, to the part to be driven.

Assume that a strain or load is imposed upon the part to be driven; it is apparent that the frame 1 will rotate about the shafts

4 and 5, as the shaft 4 is for the moment being held stationary by the load, the wheels 8 and 6 likewise being held stationary, the gear 9 will travel around the gear 8, thereby 5 rotating the frame 1 about the shafts 4 and 5. Frame 1 will rotate about the shafts 4 and 5 until the weight of the wheel 11, added to the momentum thereof plus the source of power, which has remained constant through- 10 out, is sufficient to cause the rotation of the wheel 8, the shaft 4 and wheel 6, thereby without any additional power at the source adding sufficient power, stored up or accumulated in the fly wheel, to overcome the 15 added load on the part to be driven.

For a concrete illustration, assume the wheel 14 to be connected to the sprocket wheel of a bicycle and assume the wheel 6 20 is connected to the driving wheels of a vehicle. The normal operation of turning the bicycle sprocket being imparted to the wheel 14 and thus through the connections to the wheel 6 causes the vehicle to be impelled forwardly. When, however, a load is imposed upon the vehicle, which usually would 25 require an additional source of power at the bicycle, the same amount of power at the bicycle causes the gear 9 to ride on the gear 8 until the power derived from the momentum 30 and weight of the fly wheel 11 is sufficient to operate the vehicle. It is obvious that the more load that is applied upon the vehicle the farther the gear wheel 9 will climb on the gear wheel 8, but at no time 35 is added power necessary at the source.

It is apparent that this principle may be applied in any instance where a source of power is to be transmitted to a variable load, for example, on automobiles, or the like. 40 While I have set forth one specific application of my invention and have shown and described a specific structure embodying the principles thereof, I wish it to be understood that my invention in its broad scope 45 is not to be limited thereto, as many applications and many structures embodying the principles of my invention will readily occur to those skilled in the art without departing from the broad scope of my invention, 50 as defined in the claims.

Therefore, what I claim as new and useful and of my own invention and desire to secure by Letters Patent is:—

1. In combination with a source of power, 55 and a part to be driven, means displaceable relative thereto and actuated by the source of power for accumulating energy to drive the part to be driven when additional load is applied thereto.
- 60 2. In a combination with a source of power, and a part to be driven, means interposed between the source of power and the part to be driven displaceable relative thereto, and actuated by the source of power, for 65 accumulating energy to drive the part to be

driven when additional load is applied thereto.

3. In combination with a source of power and a part to be driven, a fly wheel rotated by said source of power displaceable relative thereto, and means actuated by the rotation of said fly wheel and its movement toward its normal position from its displaced position for driving said part to be driven when additional load is applied thereto. 70

4. In combination with a source of power and a part to be driven, a fly wheel rotated by said source of power displaceable relative thereto, and means actuated by the momentum of said fly wheel and its movement toward its normal position from its displaced position for driving said part to be driven when additional load is applied thereto. 80

5. In combination with a source of power and a part to be driven, a fly wheel rotated by said source of power displaceable relative thereto and means actuated by the movement of said fly wheel to its normal 90 position from its displaced position for driving said part to be driven when additional load is applied thereto.

6. In combination with a source of power and a part to be driven, a fly wheel rotated by said source of power and means actuated by the momentum and weight of said fly wheel for driving said part to be driven when additional load is applied thereto. 95

7. In combination with a source of power, and a part to be driven, a gear system interposed between the source of power and the part to be driven, a fly wheel operated in said gear system, and means actuated by the addition of load to the part to be driven 105 for displacing the fly wheel relative to the gear system.

8. In combination with a source of power, and a part to be driven, a gear system interposed between the source of power and the part to be driven, a fly wheel operated in said gear system, and means actuated by the addition of load to the part to be driven for displacing the fly wheel relative to the gear system and means controlled by the movement of said fly wheel in returning to its normal position for supplying the additional power required to drive the part to be driven with its added load. 110

9. The combination with a frame pivotally supported on an axis off-set relative to the horizontal axis thereof, of a shaft located at the horizontal axis of said frame, a fly wheel carried by said shaft, means for rotating said fly wheel, and means actuated thereby for rocking said frame. 120

10. The combination with a frame pivotally supported on an axis off-set relative to the horizontal axis thereof of a fly wheel carried on a shaft located on the horizontal 130

axis of said frame, means for rotating said fly wheel, a part to be driven, means operated by said fly wheel for driving said part, and means actuated by the application of 5 additional load on said part for rocking said frame.

11. The combination with a frame pivotally supported on an axis off-set relative to the horizontal axis thereof of a fly wheel carried on a shaft located on the horizontal axis of said frame, means for rotating said fly wheel, a part to be driven, means operated by said fly wheel for driving said part, and means actuated by the application of 15 additional load on said part for rocking said frame, whereby the additional power acquired by said fly wheel acts to drive the loaded part to be driven.

12. The combination with a frame, of 20 pivot studs for pivotally supporting said frame, said pivot studs being located in the same axis and offset relative to the hori-

zontal axis of said frame, a shaft located in the horizontal axis of said frame, a fly wheel carried by said shaft, means for rotating one of said pivot studs, means operated thereby for rotating said shaft, means operated by said shaft for rotating the other of said pivot studs, means operated thereby for driving a part to be driven.

13. In combination with a source of power and a part to be driven mounted on the same axis of rotation, means interposed between the source of power and the part to be driven and movable relatively to said axis 35 of rotation of said source of power and part to be driven and actuated by the source of power for accumulating energy to drive the part to be driven when additional load is applied thereto.

In testimony whereof I have hereunto set my hand on this 14th day of April A. D. 1917.

NICHOLAS H. CHRISTOFFERS.
